METHOD AND COMPOSITION FOR IMPROVING MILLING PRODUCTS

Frederic H. Penn, Dallas, Tex.

No Drawing. Application June 6, 1939,
Serial No. 277,733

12 Claims. (Cl. 99—91)

My invention relates to the improvement of wheat flour and other milling products, including the baking and keeping qualities thereof, and more particularly has reference to a method and composition for the simultaneous bleaching and ageing or maturing of flour and the like.

According to present commercial practice, flour is bleached and aged in separate stages of treatment. The initial treatment is accomplished with gaseous nitrogen trichloride, which matures the flour. Nitrogen trichloride, in addition to being a maturing agent, also possesses bleaching properties, but when used in sufficient amount to obtain a complete commercial bleach, injures the quality of the flour. Therefore, for this reason nitrogen trichloride is used in an amount not substantially in excess of that required to mature or age the flour, and the necessary additional bleaching is obtained by a subsequent treatment with benzoyl peroxide, which has no maturing properties. While the last-mentioned step is relatively simple, the gas treatment is quite cumbersome, requiring special contacting apparatus and corrosion-resistant equipment and accurate control over the gas, which presents many hazards and difficulties in use.

It is an object of this invention to bleach and age flour and the like in a single operation and to provide a finely divided or powdered composition which, when intimately mixed with the flour, functions to effect a simultaneous bleaching and ageing of the milling product. The flour is thus improved in the two respects mentioned by the simple expedient of mixing the solid composition therewith and allowing sufficient time for the desired effects to take place.

In my prior Patents Nos. 2,158,588 and 2,158,589, I have shown that simultaneous bleaching and ageing of flour and the like can be obtained by means of a powdered mixture of a bromate or iodate with an active organic peroxide, the latter seemingly functioning as an activator or accelerator for the solid bromates and iodates in their maturing of the dry milling product. I have now found that water soluble salts containing heavy metals, in their acid radicals, in powdered form, similarly function with the active organic peroxides to bring about a simultaneous bleaching and ageing of flour and other milling products.

Accordingly, the solid bleaching and maturing composition of the present invention comprises a pre-formed mixture of a powdered water soluble salt containing a heavy metal in its acid radical and an active organic peroxide, that is, an organic peroxide which is sufficiently active in powdered form to effect at least a 90% flour bleach.

Potassium vanadate in powdered form is the preferred reagent for use with the active or-

ganic peroxide; sodium tungstate and potassium manganate are illustrative of other water soluble heavy metal salts suitable for use in powdered form with the active organic peroxide.

As in my prior patents referred to, only certain organic peroxides are sufficiently active to cooperate with postassium vanadate and like compounds to effect the simultaneous bleaching and maturing, these being the aromatic and fatty acid peroxides which have sufficient activity in powdered form to accomplish at least a 90% flour bleach. Benzoyl peroxide is the preferred aromatic peroxide while cinnamyl peroxide and phenyl acetyl peroxide are other aromatic peroxides which I have found to be of sufficient activity and flour bleaching power for use with potassium vanadate and the like in accordance with the invention. Suitable active fatty acid peroxides of sufficient bleaching power for my purpose are stearyl peroxide, lauryl peroxide and palmitic acid peroxide. These aromatic and fatty acid peroxides function with the finely divided or powdered salt to bring about a commercially satisfactory maturing and bleaching of dry flour. I believe that I am the first to discover that the active aromatic and fatty acid peroxides have the effect of increasing the maturing action of powdered potassium vanadate and the like upon dry milling products.

In practicing the method of this invention, the bleaching and ageing composition is fed directly into the flour at any convenient point during the milling operation and intimately mixed therewith, by means of powder feeding machines now used in the mills, in the proportion of about one-half ounce to 196 pounds of flour. For thorough distribution of such small amounts of the composition in the flour, the composition should be in the form of a dry free-flowing finely divided powder. A satisfactory bleaching and ageing is obtained by exposure of the flour to the action of the composition for about twenty-four hours.

As illustrative of the preparation of a preferred composition, dry powdered commercial grade di-calcium phosphate or other suitable carrier is added to an equal weight of dry commercial grade granular benzoyl peroxide and the mixture ground to the desired fineness. With the powder thus obtained there is now mixed dry powdered potassium vanadate in the proportion of six parts potassium vanadate to ninety parts of the peroxide-phosphate mixture. The resultant mixture is then ready for use as a flour bleaching and ageing composition in the manner already described.

Since there are many grades of flour, the proportion of peroxide, potassium vanadate and carrier, as well as the amount of the composition required for effective bleaching and maturing, should be determined by tests in partic-

ular cases. In some instances for certain kinds of flour the proportion of potassium vanadate may be increased to about eight parts to ninety parts of the peroxide-phosphate mixture and in other instances the amount of potassium vanadate may be decreased to about four parts to ninety parts of the peroxide-phosphate mixture. Ordinarily the proportion of six parts of potassium vanadate with ninety parts of the mixture of equal weights of benzoyl peroxide and dicalcium phosphate is satisfactory for many of the various grades of flour. The proportions here stated are by weight.

The compositions of this invention improve the color and baking qualities of the flour. Loaf volume is one of the most important, if not the most important, indication for determining the value of the baking qualities of flour. The volume of the baked loaf of bread is measured in cubic centimeters and denotes the exact size of the loaf produced. Small volume, as obtained with untreated or unmatured flour, indicates low baking strength, while large volume indicates high baking strength, which is apparently brought about by the maturing of the flour.

The following tabulations show, by comparison, the advantages and effectiveness of my composition. Table I deals with a hard wheat bakers' flour and Table II with a blend of hard and soft wheat flour. The tables show the amounts of benzoyl peroxide and potassium vanadate used in the tests. In each case where benzoyl peroxide was employed, it was mixed with an equal weight of dicalcium phosphate as a carrier. This is not indicated in the tables for sake of simplification. The laboratory tests were performed on amounts of fresh milled flour such that the treatments correspond to the use of about one-half ounce of the compositions per 40 196 pound barrel of flour.

TABLE I
Hard wheat bakers' flour

45		Loaf volume, c. c.	Color removal	Texture
Untreated.....		710	None	92
50 Laboratory treated benzoyl peroxide 45 gm., potassium vanadate 3 gm.....		765	99	99
Laboratory treated benzoyl peroxide 45 gm.....		668	98	95
Laboratory treated potassium vanadate 3 gm.....		740	None	98

55 TABLE II
Blend hard and soft wheat flour

60		Loaf volume, c. c.	Color removal	Texture
Untreated.....		620	None	90
65 Laboratory treated benzoyl peroxide 45 gm., potassium vanadate 3 gm.....		645	99	98
Laboratory treated benzoyl peroxide 45 gm.....		583	98	95
Laboratory treated potassium vanadate 3 gm.....		635	None	98

70 Illustrative of the valuations of the tests: The loaf volume obtained with untreated hard wheat bakers' flour, which is fresh milled flour without any kind of treatment, is 710 c. c. The same untreated fresh milled hard wheat bakers' flour laboratory treated with the benzoyl peroxide, 75 potassium vanadate composition yields a loaf

volume of 765 c. c., an increase of 55 c. c. more than is obtained with untreated flour. Untreated hard wheat flour laboratory treated with benzoyl peroxide alone and in an amount to effect a complete commercial bleach of the flour yields a 5 loaf volume of 668 c. c., a reduction of 42 c. c. in volume less than is obtained with untreated flour. Laboratory potassium vanadate treated hard wheat flour yields a loaf volume of 740 c. c., an increase in volume of 30 c. c. above the volume 10 obtained with untreated hard wheat flour.

According to the tests, benzoyl peroxide when used alone and in sufficient quantity for a complete bleach of the flour reduces the loaf volume. Potassium vanadate when used alone matures the 15 flour somewhat but not to as great an extent as when mixed with the peroxide and it does not have any bleaching effect. When benzoyl peroxide and potassium vanadate in combination are incorporated into the dry flour during the milling 20 process a complete bleach and color removal is obtained with an increase in loaf volume which is in excess of the volume obtained when either potassium vanadate or benzoyl peroxide is used alone.

In the appended claims I have characterized the organic peroxides as active and as having substantial flour bleaching properties in order to distinguish from those organic peroxides which are of insufficient activity and bleaching power 30 to effect a commercial bleach. By "substantial flour bleaching properties" is meant the ability to bleach flour satisfactorily for commercial purposes, that is, to effect at least a 90% bleach.

Having described my invention, I claim: 35

1. A method for improving wheat flour and other milling products which comprises intimately mixing with the dry milling product a powdered water soluble salt containing a heavy metal in its acid radical and a powdered active 40 organic peroxide having substantial flour bleaching properties, the peroxide being in sufficient amount to bleach the milling product and said salt being in sufficient amount to increase the loaf volume factor of the milling product, and 45 subjecting the milling product in dry form to the simultaneous action of said salt and peroxide for a sufficient time to bleach and mature the product.

2. A method for improving wheat flour and 50 other milling products which comprises intimately mixing with the dry milling product a powdered water soluble salt containing a heavy metal in its acid radical and a powdered active aromatic peroxide having substantial flour bleaching properties, the peroxide being in sufficient amount to bleach the milling product and said salt being in sufficient amount to increase the loaf volume factor of the milling product, and subjecting the milling product in dry form to the simultaneous 55 action of said salt and peroxide for a sufficient time to bleach and mature the product.

3. A method for improving wheat flour and other milling products which comprises intimately mixing powdered benzoyl peroxide and a powdered water soluble salt containing a heavy metal in its acid radical with the dry milling product, the peroxide being in sufficient amount to bleach the milling product and said salt being in sufficient amount to increase the loaf volume factor of the milling product, and subjecting the latter in dry form to the simultaneous action of the peroxide and said salt for a sufficient time to bleach and mature the milling product.

4. A method for improving wheat flour and 75

other milling products which comprises intimately mixing powdered benzoyl peroxide and potassium vanadate with the dry milling product, the peroxide being in sufficient amount to bleach the milling product and said vanadate being in sufficient amount to increase the loaf volume factor of the milling product, and subjecting the latter in dry form to the simultaneous action of the peroxide and potassium vanadate for a sufficient time to bleach and mature the milling product.

5. A method for improving wheat flour and other milling products which comprises intimately mixing powdered benzoyl peroxide and sodium tungstate with the dry milling product, the peroxide being in sufficient amount to bleach the milling product and said tungstate being in sufficient amount to increase the loaf volume factor of the milling product, and subjecting the latter in dry form to the simultaneous action of the peroxide and sodium tungstate for a sufficient time to bleach and mature the milling product.

6. A method for improving wheat flour and other milling products which comprises intimately mixing powdered benzoyl peroxide and potassium manganate with the dry milling product, the peroxide being in sufficient amount to bleach the milling product and said manganate being in sufficient amount to increase the loaf volume factor of the milling product, and subjecting the latter in dry form to the simultaneous action of the peroxide and potassium manganate for a sufficient time to bleach and mature the milling product.

7. A flour bleaching and maturing composition comprising a dry free-flowing powdered mix-

ture of a water soluble salt containing a heavy metal in its acid radical and an active organic peroxide having substantial flour bleaching properties, said salt being in sufficient quantity to overcome the loaf volume reducing factor of the peroxide.

8. A flour bleaching and maturing composition comprising a dry free-flowing powdered mixture of a water soluble salt containing a heavy metal in its acid radical and an active aromatic peroxide having substantial flour bleaching properties, said salt being in sufficient quantity to overcome the loaf volume reducing factor of the peroxide.

9. A flour bleaching and maturing composition comprising a dry free-flowing powdered mixture of a water soluble salt containing a heavy metal in its acid radical and benzoyl peroxide, said salt being in sufficient quantity to overcome the loaf volume reducing factor of the peroxide.

10. A flour bleaching and maturing composition comprising a dry free-flowing powdered mixture of benzoyl peroxide and a sufficient quantity of potassium vanadate to overcome the loaf volume reducing factor of the benzoyl peroxide.

11. A flour bleaching and maturing composition comprising a dry free-flowing powdered mixture of benzoyl peroxide and a sufficient quantity of sodium tungstate to overcome the loaf volume reducing factor of the benzoyl peroxide.

12. A flour bleaching and maturing composition comprising a dry free-flowing powdered mixture of benzoyl peroxide and a sufficient quantity of potassium manganate to overcome the loaf volume reducing factor of the benzoyl peroxide.
